NICHOLAS S. VEDDER, OF TROY, NEW YORK.

Design No. 2,738, dated August 6, 1867.

DESIGN FOR THE DOORS OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Design for Stove-Doors, of which the following is a full and exact description, reference being had to the accompanying photographs of two stove-doors, in each of which my said design is represented.

This design consists of the particular compound ornamental rod and vine *g*, shaped and arranged along and around the edge or outer moulding of a stove-door so as to make the border thereof present an appearance like that represented in Figure 1 or Figure 2 of the accompanying photographs.

What I claim as my invention or production, and desire to secure by Letters Patent, is—
The design for the border, of stove-doors, herein set forth and shown.
